poration of New York

Application June 5, 1936, Serial No. 83,705
In Germany June 11, 1935

1 Claim. (Cl. 178—7.6)

In the earlier application Ser. No. 22,115/35 the applicant has described a method which permits of the scanning of a continuously moved film according to the interlaced line-group method. 5
5 This method is based on the use of a multiple-spiral disc, whereby the number of spirals have been made equal to the number of groups of lines of which an image is composed. In the case of a film moved at the rate of 25 images per second and a decomposition of each film image into two part-images there rotated, for example, a disc having two spirals, of which each spiral was half the height of the film image, at 50 revolutions per second, in such fashion that the apparent radial movement of the image points is directed in opposition to the apparently radial movement of the projected film image. 10
10 In the present application there is retained the essence of the idea disclosed in the cited earlier application No. 22,115/35 of October, 1934. As in the latter there is employed in the present case a multiple-spiral disc, for example a disc having two connective image-point spirals, whereby the image points follow up radially in a direction opposite to the movement of the projected film image. The difference between the two methods resides in the production of the line displacement. If, in the manner described in the earlier application, there are employed an even number of image points, for example 2 x 120 image points, on the spiral aperture disc, a line displacement can only be obtained at the receiving station if upon the reception the relaxation oscillation commences and ends upon each second relaxation period to the extent of the width of one line higher or lower than the preceding period. 15
15 The vertical relaxation oscillation must perform in addition to the normal scanning movement a rocking movement of the height of a line width, i. e., the so-called line jump. In order to produce this line jump at the receiving station it was necessary in accordance with the earlier method to transmit from the sending end image-change impulses, of which each second one arrived to the extent of one-half of a line period too early or too late as compared with a sequence of exactly isochronous impulses. It was accordingly necessary to transmit the image-change signals in the form of a group each comprising 20
20 two anisochronous part-impulses. This does not present any difficulties in itself, and solutions in respect of transmitters and receivers are set forth in several earlier applications. On the other hand the anisochronous impulse method 25
25 represents an increased load on the vertical relax-

ation apparatus of the receiver, as the same may no longer perform relaxation between two fixed limits, viz., the upper and lower edge of the image, but must perform the relaxation with good repetition rest in alteration altogether between four limits. It is subject matter of the present invention to depart from the method employing the anisochronous image-change signals by the fact that there is introduced a well defined detuning of the line frequency as compared with the harmonic vibration condition between the line and image-change periods. By reason of this detuning method it is possible to operate with purely isochronous image-change signals without the necessity for any line-jump movement in the case 5 of the receiver screen. The receiver screen in the case of the new method may perform relaxation between merely two fixed limits exactly as in the reception of simple television transmissions, and does not require to perform anything beyond that 10 called for in the case of television with simple 15 standard of scanning.

The fundamental idea consists in the fact that a line displacement occurs automatically when an odd number of lines are employed for continuously moved films as described in the following 20 specification.

The novel features which I believe to be characteristic for my invention are set forth with particularity in the appended claims. My invention, however, both as to its organization and method of operation together with further objects and advantages thereof may be best understood by reference to the following description taken in connection with the accompanying 25 drawings, in which

Fig. 1 shows in principle the production of the line displacement with an odd number of scanning holes, whilst

Fig. 2 shows a scanning disc with a double 30 spiral arrangement of the scanning holes.

Fig. 3 is intended to explain the manner in which the decomposition of the image is brought about.

Fig. 4 shows the principle of a multiple spiral 35 disc, particularly a disc having four complete spirals.

Fig. 5 serves to explain an operation of a multiple spiral disc, whilst

Fig. 6 shows an arrangement of producing syn- 40 chronisation impulses, to which further reference is made in the following paragraphs.

In particular referring to Fig. 1 an image area 45 is scanned in three lines and two groups of lines, so that accordingly each group of lines com- 50

55

prises one and a half lines. The first group of lines comprises the lines a_1 and a_2 , the second group of lines the lines b_1 and b_2 . It is to be recognized that the group of lines b is disposed 5 in the intermediate spaces of the group of lines a without it being necessary for the vertical screen apparatus to depart from the two limiting points c , the upper edge of the image, and d , the lower edge of the image. An oscillation of this 10 kind between two fixed lines of limitation can be produced and maintained in the usual fashion with isochronous synchronisation signals. The applicant formulates the condition under which 15 a line displacement of this nature occurs automatically between the groups of lines by the following formula:

$$z = b \cdot n + 1$$

In this z is the total number of lines in which 20 the image appears in decomposed form. z , therefore, is the actual "screen quality" and determines the frequency band width of a transmitter of this character. b is the number of part-images produced one over the other, n the number of lines employed for each part image. It 25 is an essential feature that z be an odd number. Possible combinations are, for example:

$$\begin{aligned} b &= 2 \\ n &= 120 \\ z &= 241 \end{aligned}$$

or

$$\begin{aligned} b &= 3 \\ n &= 100 \\ z &= 301 \end{aligned}$$

35 The number of lines is fractional in respect of each part-image.

In Fig. 2 there is shown a scanning disc suitable for the transmission of 2×120 lines. The 40 sectional area on to which the film image is projected is designated 2. The same is formed by two radii 3 and 4, which are taken through the points 1 and 239, the two extreme image points of a double spiral. The double spiral itself is an Archimedian spiral running continuously from number 1 to number 239 without interruption and without irregularities. A double spiral of this kind has a central point, in the present case the point 120. This central 45 image point is situated exactly at the centre of the sectional area of the disc. α , the angle between each two radii of a disc of this kind, is represented in the case of n points by

$$\frac{720^\circ}{n}$$

55 This angle amounts for example in the case of a disc having 239 points to $3^\circ 0' 45''$; in the case of a disc having 2×89.5 lines, i. e., $n=179$ image 60 points, the angle is, for example, $4^\circ 1' 30''$. A transmission with a disc of this kind will be performed with advantage in conjunction with the so-called "self-synchronising image point" method. If the disc, viewed from the projection 65 light, rotates clockwise, as shown in Fig. 2, each image element must traverse a starting line 5 at the edge of the image on the left hand side. This is accentuated in relation to the image by particularly bright lighting and provides the line 70 synchronisation signal with excess of amplitude. For sorting out the two image-point spirals there is combined with the disc according to Fig. 2 a spiral diaphragm, which is designated 6 in Fig. 2 and rotates in the same direction at half 75 the circumferential velocity. In practice the

circumferential velocity of the disc is, for example, 6000 R. P. M. and that of the diaphragm 6 3000 R. P. M. The diaphragm may rotate in the plane of an optical intermediate image, in which manner diaphragm screening may be obtained without loss of light or lack of sharpness of the diaphragm shadow.

In addition to the line synchronisation, which is effected by the starting line, there is also required an image-change synchronisation. This 10 is obtained by a single synchronisation slot 7. This synchronisation slot, cuts a projection 5' of the starting line 5, which may be regulated by means of a shiftable gap, so that the height of the light signal of the slot 7 is just as great 15 as the height of the line impulse over the starting line 5. The image-change slot 7, on each occasion when it passes through the starting line 5', is freed up to the photo-cell. For this purpose the shading diaphragm 6 is furnished 20 with two recesses 8 and 9 which are generously dimensioned in the peripheral direction. The length of the slot 7 determines the duration of darkening of the vertical return line. It has been found that in the television art a duration 25 of the return amounting to 1% is fully adequate. 7 may accordingly have the length of 1-3 line periods.

To explain the manner in which the decomposition of the image is brought about there is 30 also provided Fig. 3. In Fig. 3 there is to be seen in what manner the reproduction of the original film passes over the decomposing points of the disc and both sections move one against the other. The movement of the film image 10 35 is divided into 7 phases. The image moves evenly from the bottom towards the top and the image points of the disc move at the same rate but in opposition from the top towards the bottom. The disc contains seven points and 40 decomposes the film into 2×3.5 lines. In phase a there operates the point 4. Up to the phase b it has scanned the topmost line 1 of the reproduction of the film. At b phase there commences the point 5, and up to phase c it has scanned 45 the line 3. In phase c there commences the point 6 which up to phase d has scanned the line 5. In phase d the lowermost point 7 scans line 5 of the original. It does not complete this, however, but moves away from the original image 50 at the lower edge after completion of a half-line. At this moment the image change impulse commences. The commencement of the image change signal is entered as 7. By reason of the jump in the disc section from the point 55 7 to the following point 1 there is initiated the scanning of the second group of lines. A condition for this is, in accordance with the invention:

The height of the projected film image amounts 60 to so many line widths as there are image points on the disc.

The point 1 passes during e over the line 2, which was free. The point 2 passes during f over the line 4, which was previously free, and 65 in similar fashion the point 3 scans the line 6 during g . Point 4 is unable to reach the original image, which has now been completely scanned twice, and already commences the scanning of the next image. Phase h accordingly 70 follows on phase a . At this moment, in accordance with the invention, there must commence the second image-change signals 7'. The position of both image-change signals is exactly isochronous. The spacing of the two sig- 75

nals amounts to half the total of all line periods. This condition is satisfied by provision of the synchronisation slot shown in Fig. 2. The end of this slot 7 requires to pass exactly over the projection 5' of the starting line 5 when the radius of the middle point passes through the central image point and the middle of the image area.

It is possible in accordance with the above statements to design other transmission discs for a different number of lines and for a different number of part-image transmissions. In this connection the number of complete spiral turns is always equal to the number of part-image transmissions if the disc rotates as many times per part-image as image repetitions are desired. The total height of jump of all spirals is equal to the height of reproduction of the film image.

It is, however, also possible to make the arrangement in accordance with the diagram in Fig. 3 in those cases in which the disc performs twice the number of revolutions.

For comparatively large numbers of lines it is advisable to employ scanning discs operating at high speeds. A further feature of the invention is a disc of this kind which effects scanning according to the interlaced line-group method, whereby the image appears in decomposition into an odd number of lines. In contradistinction to the scanning disc described in connection with Fig. 2 which rotates twice for a single image transmission and contains two spiral turns, there is shown in Fig. 4, for example, as representative of the high speed discs according to the invention a disc having four spirals which rotates four times for each image transmission. In the case of 25 images per second this disc requires to perform 6,000 revolutions per minute. The disc carries an odd number of image points corresponding with the total number of lines transmitted per image, for example 179 or 239 image points. Each image point encloses with the succeeding one a central angle α , which is represented by the formula

$$\alpha = \frac{n \cdot 2\pi}{z}$$

n being the number of complete spirals and z the number of image points applied. In the present case, Fig. 4, n is equal to 4 and z is as stated. The following are essential features as regards the subject matter of the invention:

1. The disc performs n revolutions upon movement of the film to the extent of the height of one image.

2. Radial movement of the image points on the disc is in opposition to the movement of the film reproduction on the disc.

3. Total height of the disc section is equal to the total height of the film reproduction, i. e., $=z$ line widths of z image points are present.

4. The middle image point with the number $z+1/2$ bisects the angle formed between the points 1 and z .

If the first and last points of the disc, number 1 and number 5 or, generally speaking, z , are connected by a secant, this secant must meet the middle point 3 or, generally speaking,

70

$$1 + \frac{z}{2}$$

This middle point bisects the angle α formed between 1 and z . The points of intersection 3 and 4 of the secant with the spirals likewise meet

image points with the disc, which rotates clockwise, there runs in the ratio of

$$\frac{1}{n}$$

i. e., in the present case at 1,500 revs., a shading diaphragm 6. This shading diaphragm may be reproduced either immediately in front of the disc, i. e., so that it throws a comparatively sharp shadow on to the disc, or it may also be reproduced in accordance with the invention in the intermediate image of the disc. To explain the intermediate-image method the plane of the disc is designated 23 in Fig. 5. The film 25 is reproduced sharply on this disc by means of a lens 24. By means of an auxiliary lens 25' there is again produced from the image on the disc 23 an intermediate image 26 and in this intermediate image there rotates the said diaphragm 6. Behind this there may be connected the photocell 11 either in direct fashion or with the interposition of a collimator 10.

The synchronisation in the case of all of these discs according to the invention having an odd number of apertures is effected by means of a synchronisation slot 7. The slot 7 must commence with the same central angle either with the point 1 or with the middle point

$$1 + \frac{z}{2}$$

30

The slot is uncovered as many times as part-images are to be disposed one over the other. In the present case the slot is uncovered twice upon four revolutions of the main disc. By reason of the bisecting of the angle α by the middle section point in accordance with the invention it is accomplished that each part-image is scanned to the extent of one-half of a line period too late as compared with the preceding one and in this way the line-group displacement is brought about automatically with the use of a harmonic sequence of image-change signals 7.

The method as set forth is contemplated primarily in conjunction with synchronisation by means of a starting line. More concise statement in this connection is included in connection with 2 and the starting line has been designated 5 and 5' respectively in Figs. 1 and 4. It is also possible to employ a light screen, which contains a special row of slots 14. In order to obtain the characteristic line synchronisation frequency a slot 14 must be provided in accordance with the invention for every radius taken from any image point to the central point, and in addition there must be employed a frequency reduction in the ratio of $1:n$. This frequency reduction may be produced in simple fashion electrically, preferably by the use of a relaxation connection.

In Fig. 6 there is shown an arrangement of this kind. The disc having 4 or 2 spirals and rotating with 6,000 or 3,000 revolutions generates with its apertures in conjunction with a lighting means 15 and a photo-cell 16 behind a slot tone amplifier 17 a control frequency. This is not capable of being employed in direct fashion for synchronisation of the received image. In accordance with the invention it is passed to frequency reducer 18. This frequency reducer 18 may consist of a flash connection, in which a condenser 19 is charged by a resistance 20 with a frequency of $1/4$ or $1/2$ of the aforesaid slot frequency. In the manner well known per se there is then employed merely every second or every fourth oncoming change for the synchronisation of an ignition in the

- thyatron 21. All remaining changes pass through unutilised. At a transformer 22 an impulse series may accordingly be tapped as sub-harmonic. This may be employed, possibly after filtering, in immediate fashion for synchronisation of the receiver in the case of operations of this kind with interlaced groups of lines. An advantage of this method of frequency reduction with synchronously rotating sirenes in accordance with the invention is to be regarded in the fact that no conjointly rotating screening diaphragms are required, and that a single synchronously rotating shaft is sufficient for solving the problem.
